COMBINED JAR AND DISPENSING CLOSURE

James O. Roberts, Cleveland Heights, Ohio, assignor to Owens-Illinois, Inc., Toledo, Ohio, a corporation of Ohio

Filed Dec. 1, 1967, Ser. No. 9,609

Term of patent 14 years

(Cl. D9—131)

FIG. 1

The side opposite that seen in FIGURE 1 is the same in appearance as the side shown.

I claim:

The ornamental design for a combined jar and dispensing closure, substantially as shown and described.
